UNITED STATES PATENT OFFICE.

JOSEPH L. FRITZ, OF PHILADELPHIA, PENNSYLVANIA.

DESIGN FOR A COVER FOR VENT-BOXES.

54,735.

Specification for Design.

Patented Mar. 23, 1920.

Application filed March 11, 1919. Serial No. 282,043. Term of patent 7 years.

To all whom it may concern:

Be it known that I, JOSEPH L. FRITZ, a citizen of the United States, and a resident of Philadelphia, county of Philadelphia, and State of Pennsylvania, have invented a certain new, original, and ornamental Design for a Cover for Vent-Boxes, as shown in the accompanying drawings, in which—

Figure 1 is a top plan view of the cover; Fig. 2 is a side edge elevation of the same; Fig. 3 is a front elevation of the same; and Fig. 4 is a bottom plan view of the same.

I claim:

The ornamental design for a cover for vent boxes substantially as shown.

In witness whereof, I have hereunto set my hand this eighth day of March, A. D., 1919.

JOSEPH L. FRITZ.
